US0D1081736S

(12) **United States Design Patent** (10) Patent No.: **US D1,081,736 S**
(45) Date of Patent: ** Jul. 1, 2025

(54) **LASER ENGRAVING DEVICE**

(71) Applicant: **Shenzhen Creality 3D Technology Co., Ltd.**, Shenzhen (CN)

(72) Inventors: **Huilin Liu**, Guangdong (CN); **Jinghao Wei**, Guangdong (CN); **Fayang Cao**, Guangdong (CN); **Meifeng Su**, Guangdong (CN)

(73) Assignee: **Shenzhen Creality 3D Technology Co., Ltd.**, Shenzhen (CN)

(**) Term: **15 Years**

(21) Appl. No.: **35/518,305**

(22) Filed: **Sep. 13, 2022**

(80) **Hague Agreement Data**

Int. Filing Date: **Sep. 13, 2022**

Int. Reg. No.: **DM/223606**

Int. Reg. Date: **Sep. 13, 2022**

Int. Reg. Pub. Date: **Sep. 15, 2023**

(30) **Foreign Application Priority Data**

Mar. 30, 2022 (CN) 202230174326.1

(51) LOC (15) Cl. **15-09**

(52) U.S. Cl.

USPC **D15/122**

(57) **CLAIM**

The ornamental design for laser engraving device as shown and described.

DESCRIPTION

1. Laser engraving device
- 1.1 : Perspective
- 1.2 : Perspective
- 1.3 : Perspective
- 1.4: Front
- 1.5 : Back
- 1.6 : Left
- 1.7 : Right
- 1.8: Top
- 1.9 : Bottom

The design is a product configured for laser engraving. The broken lines in the reproductions depict portions of the article which form no part of the claimed design.
